**CONCENTRATED LIQUID ACETIC ACID DOUCHE
PREPARATION CONTAINING AROMATICS**
Galen F. Collins, Oscar L. Butt, and Buford Leroy Poet,

Bristol, Tenn., a corporation of Tennessee
No Drawing. Filed Jan. 27, 1965, Ser. No. 428,555
3 Claims. (Cl. 167—58)

This invention in one of its aspects pertains to liquid douche compositions. In one of its more particular aspects the invention relates to liquid douche compositions which, although in aqueous phase, nevertheless contain aromatics. The term "aromatics" as used in connection with douches in powder form is well known and is understood to encompass one or more of menthol, thymol, oil of eucalyptus, methyl salicylate, and the like, all of which are virtually insoluble in water. See Modern Drug Encyclopedia and Therapeutic Index, Drug Publications, Inc.

A study of textbooks on gynecology reveals divergent views on douching. Some physicians advocate acid douches; some prefer alkaline douches; and there are those who advocate no douching. It is generally believed, however, that while many vaginal symptoms can be cleared up only by the removal of deep-seated causes, the therapeutic vaginal douche serves as an important adjuvant in the treatment of such conditions. In addition a surprising number of minor infections appear to be cured by the use of acid douche preparations.

It has been reported that alkaline douches have no application in therapy of vaginitis. Vaginal therapy for *Trichomonas vaginalis* vaginitis depends upon the restoration of the vaginal pH to a normal range of 3.5 to 5. Treatment for vaginal vaginitis and for nonspecific vaginitis consists of acid douching. The selection of a suitable douche is, therefore, a matter of great importance to the clinician.

This invention is concerned with acid douche preparations used to restore and maintain an acid pH corresponding to that of the normal lactobacillary flora of the vaginal tract. These are liquid preparations used as adjuncts in the management of vaginal and cervical infections due to trichomonas and other vagino-cervicitis infections. There are certain advantages to the use of liquid douche preparations for feminine hygiene. A liquid preparation has all of the active ingredients dissolved. This eliminates

2

possible irritations that may occur in the case of powder douche preparations due to the fact that all of the solid materials or oils are not in solution prior to use. Moreover a liquid preparation is easier to use since the product does not require any significant stirring for preparation for use. A liquid also lends itself to measuring devices such as bottle caps which find better consumer acceptance.

In spite of the advantages of liquid douche preparations they have not been as widely accepted as powder douche products. One reason for this is believed to be that liquid douche preparations do not include the effective aromatics. Experience has shown that combinations have excellent acceptance by users of powder douche products which contain menthol, oil of eucalyptus, methyl salicylate and thymol, and various mixtures of these. These aromatics have such low solubility in water they have heretofore been used only in powders. Powder douche preparations are highly diluted with water; this permits solution of the aromatics.

One possible method for incorporating aromatics in a liquid douche preparation would be to dissolve the aromatics in a water-soluble alcohol and dissolve this alcohol solution of aromatics in water. However in the case of an acid douche, an alcohol-acid reaction is possible. Desirable acid douches should provide a pH between 3.5 and 5 with good buffer capacity. The acid-alcohol reaction and accompanying ester formation will raise the pH and reduce the buffer capacity of the douche preparation. It is therefore not possible to maintain the desired pH if a reaction occurs between the acidic material and the alcohol. In addition esters introduce unexpected odors or a foreign substance undesirable from a psychological standpoint.

In accordance with one aspect of this invention it has been found that the combination of acetic acid and isopropyl alcohol can be used in a liquid douche preparation with essentially no reaction of alcohol with acid. An indication of the alcohol-acid reaction is the percent titratable acidity. This percent acidity is determined from cubic centimeters of standard sodium hydroxide, titrating with 0.1 N sodium hydroxide using a phenolphthalein end point. The percent acidity decreases with increasing alcohol-acid reaction. It would be expected that acetic acid would form esters with ethanol at about the same rate as with isopropanol. The following data show that this is not the case.

TABLE I.—ESTERIFICATION TEST

Composition A		Composition B	
Acetic Acid, gm.....	12.5	Acetic Acid (glacial), gm.....	12.5
Ethyl Alcohol 95%, ml.....	31.5	Isopropyl Alcohol 99%, ml.....	41.1
Sodium Hydroxide, gm.....	0.5	Isodium Hydroxide, gm.....	0.5
Water, q.s., ml.....	100.0	Water, q.s., ml.....	100.0
pH, approximately.....	3.6	pH, approximately.....	3.5

ACIDITY

Composition:	Ingredient	Time Elapsed	Percent Acidity		
			CRT	40° C.	50° C.
A.....	Acetic Acid in 30% Ethanol.....	Initial.....	12.33		
		1 month.....	11.91	10.92	9.95
		9 months.....	10.18	9.32	8.99
		Initial.....	11.6		
B.....	Acetic Acid in 30% Isopropanol.....	1 month.....	11.6	11.4	11.1
		2 months.....	11.4	11.2	11.0
		3 months.....	11.3	11.0	10.6
		5 months.....	11.2	10.8	10.5

The foregoing data show that in the case of acetic acid, commonly employed in douche preparations, there is a drop in the percent acidity at controlled room temperature (CRT) from 12.33 to 10.18 in 9 months with ethanol. With the composition of this invention using isopropyl alcohol there was virtually no change in five months. The percent acidity changed from 11.6 to only 11.2 at the end of five months. It can be seen, therefore, that very little reaction occurs between isopropyl alcohol and acetic acid. Such is not the case with ethyl alcohol and acetic acid. The use of this combination is hampered only by the odors of the materials which require adjustment in proportions of the various aromatics.

It has been pointed out that in addition to providing a pH of 3.5 to 5 an effective liquid douche should have good buffer capacity. Buffer capacities can best be discussed in terms of the buffer index. Buffer index is the increment of base required to produce an increment in the pH value of the solution. Buffer index as used herein is the amount of standard sodium hydroxide, expressed in millimoles, necessary to produce an increase from the original pH to pH 6.0.

Calculation: Buffer index: millimoles of NaOH = ml. of NaOH added $\times$ normality of NaOH.

TABLE II.—BUFFER INDEX

	Ingredient	Time Elapsed	Buffer Index		
			CRT	40° C.	50° C.
Composition:					
A	Acetic Acid in 30% Ethanol	Initial	20.15		
		1 month	19.33	17.57	16.12
		9 months	16.34	14.83	14.18
B	Acetic Acid in 30% Isopropanol	Initial	18.75		
		1 month	18.73	19.15	19.20
		2 months	18.70	18.03	17.65
		3 months	17.60	17.25	16.55
		5 months	18.08	17.33	16.83

It can be seen from Table II that composition A does not have the buffer capacity which composition B of this invention possesses. There is a marked drop in buffer index in the tests conducted with composition A whereas there is little or no drop in buffer index in the case of composition B.

Acetic acid lends itself admirably to concentrated liquid douche preparations when isopropanol is employed as the vehicle for the introduction of the aromatics. According to an aspect of this invention therefore, a liquid douche preparation containing aromatics is provided, which is water dilutable, to form an aqueous douche for restoring and maintaining a normal vaginal pH. The douche preparation is a buffered aqueous solution of acetic acid having a pH of 3.5 to 5. It contains (1) a surfactant or wetting agent, and, (2) dissolved therein, an isopropyl alcohol solution of aromatics, the combination permitting solution with essentially no reaction of alcohol with acetic acid to raise the pH.

The douche preparation of this invention desirably is diluted 100 to 1000 parts to 1 by volume and will usually be sold with a device dispensing an amount to which a quart of water should be added. A douche preparation must, of course, not be harsh or irritating if used in stronger dilution since experience has shown that exact dilutions will not be used due to carelessness. The preparation of this invention can be so used.

This first aspect of the invention thus provides a liquid acetic acid douche preparation containing aromatics for use in the restoration of the vaginal pH to a normal range of 3.5 to 5, this aqueous douche composition containing 96 to 74 weight percent acetic acid as an active ingredient; 2 to 14 weight percent of a surfactant; and 2 to 12 weight percent aromatics, the total being 100 percent. The buffering is well known, sufficient alkali being used to adjust the pH in the 3.5 to 5 range. Other ingredients such as known astringents, colorants and the like can, of course, be added. The percentages of the foregoing essential in-

gredients will not change regardless of the quantity of alcohol, water or other ingredients added. The alcohol employed in the concentrated composition generally will be sufficient to dissolve the aromatics up to fifty percent of the water in the concentrate.

In the preparation of the douche compositions of this invention the aromatics can be dissolved in the isopropanol and the water-soluble ingredients dissolved in water. The two solutions are then combined. Another method is illustrated in the following example. In use, 10 ml. of the preparation is added to a quart (approximately 1000 ml.) of water. Accordingly, the examples herein are based on 10 ml. doses.

EXAMPLE A

Per 10 ml. dose

Acetic acid (glacial)	mg	500
Sodium hydroxide	mg	20
Tartrazine F.D. and C. Yellow No. 5	mg	0.25
Quinoline yellow, water soluble D. and C. Yellow No. 10	mg	1.50
Isopropanol (30%)	cc	4.0
Octylphenoxy polyethoxy ethanol Triton X-100	mg	150.0

by both the physician and the patient. It maintains the normal vaginal pH. It has cleansing and antiseptic properties due to the surfactant. It is safe, and it contains the aromatics which experience has shown are in greater demand.

Many physicians, however, prefer that a douche preparation also have mild astringent properties, aluminum salts generally being employed. Boric acid and citric acid cannot be used in liquid preparations with aluminum salts, since both aluminum borate and aluminum citrate are relatively insoluble. In another of its aspects this invention provides a unique combination of astringents which overcome this solubility problem. In accordance with the practice of this aspect of the invention novel astringents have been found which in the combination produce the normal vaginal pH. This aspect of the invention contemplates the use of an aluminum chlorhydroxide complex

wherein x is one to ten, and aluminum chloride in combination with acetic acid to provide a douche preparation with astringent properties. The following example illustrates the preparation of a liquid douche product of this aspect of the invention.

EXAMPLE B

Per 10 ml. dose

Acetic acid (glacial) -----	mg	335
Aluminum chlorhydroxide complex -----	mg	225
Aluminum chloride, hydrous (U.S.P.) -----	mg	350
Quinoline yellow, water soluble D. and C. Yellow No. 10 -----	mg	1.5
Tartrazine F.D. and C. Yellow No. 5 -----	mg	0.25
Aromatics ¹ -----	mg	90
Octylphenoxy polyethoxy ethanol (Triton X-100) -----	mg	150.0
Isopropyl alcohol (U.S.P. 99%) -----	ml	4
Water, q.s. -----	ml	10.0
¹ Aromatics:		
Menthol -----	Gm	40
Thymol -----	Gm	29.6
Oil Eucalyptus -----	Gm	29.6
Methyl Salicylate -----	Gm	38.6
		2.2
		100.0

To make this douche preparation the water is separated into two moieties. In one portion the acetic acid, aluminum chlorhydroxide complex, aluminum chloride, quinoline and tartrazine are dissolved in the amounts shown above for each 5 ml. quantity in the moiety. In the other moiety the alcohol, aromatics and surfactant are dissolved in the quantities shown per 5 ml. of moiety. A pH of 3.7 results.

Combinations of an aluminum chlorhydroxide complex and aluminum chloride have not, to our knowledge, been employed as astringents for the vaginal tract. In addition it was not realized that their use in combination with acetic acid would provide a composition possessing the buffer capacity of the douche preparation of this invention. When used in a weight ratio in the range of 1 aluminum chlorhydroxide complex:1.5 aluminum chloride:2 acetic acid, to 1 aluminum chlorhydroxide complex:2 aluminum chloride:3 acetic acid resulting in a pH of 3.5 to 5, a douche product with good buffer capacity results. Using the foregoing ratios the ingredients are employed in ranges set forth hereinbefore. The aluminum chlorhydroxide complex and aluminum chloride are the buffer ingredients, constituting 1.5 to 20 percent of the composition.

Thus this invention provides not only a liquid douche preparation containing aromatics, but a liquid douche preparation containing new and unique astringents. All of the advantages of acid douches are attained by the preparations of the invention. Obviously changes in the other ingredients can be made. For example, several combinations of aromatics can be employed, and these can be

varied depending on the alcohol employed. These and other obvious ramifications and variations are, of course, within the scope of this invention.

What is claimed is:

1. A concentrated liquid douche preparation containing aromatics, said preparation being water dilutable to form an aqueous douche for restoring and maintaining a normal vaginal pH, said preparation being a buffered aqueous solution of acetic acid having a pH of 3.5 to 5 and containing a wetting agent selected from the group consisting of sodium lauryl sulfate and nonionic surfactants, and, dissolved therein, an alcohol solution of aromatics selected from the group consisting of menthol, thymol, oil of eucalyptus, methyl salicylate and mixtures thereof, the alcohol permitting solution of the aromatics in the buffered aqueous acid solution, the alcohol being isopropanol, essentially no reaction of this alcohol with acetic acid occurring to raise the pH, the solution containing 96 to 74 weight percent acetic acid, 2 to 14 weight percent wetting agent, 2 to 12 weight percent aromatics, the total being 100 percent, and at least sufficient alcohol to dissolve the aromatics.
2. The douche preparation of claim 1 wherein the wetting agent is an octylphenoxy polyether ethanol having three to thirty oxyethylene groups.
3. A concentrated douche preparation, said preparation water dilutable to form an aqueous douche for restoring and maintaining a normal vaginal pH, said preparation containing in aqueous solution 96 to 74 weight percent acetic acid as an active ingredient, 2 to 14 weight percent of a nonionic surfactant, 2 to 12 weight percent aromatics selected from the group consisting of menthol, thymol, oil of eucalyptus, methyl salicylate and mixtures thereof, the total being 100 percent, aluminum chlorhydroxide and aluminum chloride as astringents and buffer ingredients to maintain a pH of 3.5 to 5, the weight ratio of aluminum chlorhydroxide to aluminum chloride to acetic acid being in the range of 1:1.5:2 to 1:2:3, and isopropanol, the isopropanol having the aromatics dissolved therein permitting solution of the aromatics in the aqueous acetic acid solution with essentially no reaction with acetic acid raising the pH, the volume of isopropanol being sufficient to dissolve the aromatics to 50 percent of the aqueous solution in volume.
